UNITED STATES PATENT OFFICE

NELSON K. SMITH, OF LOS ANGELES, CALIFORNIA, ASSIGNOR TO BYRON-JACKSON CO.,
OF LOS ANGELES, CALIFORNIA, A CORPORATION OF DELAWARE

WELL PIPE ELEVATOR HINGE

Original application filed December 7, 1929, Serial No. 412,479. Divided and this application filed June 30, 1931. Serial No. 547,810.

This invention relates to elevators of the type employed for raising and lowering well casing, pump tubing, and the like, in the operations of drilling a well and maintaining the well in production after it is drilled; 5 it relates particularly to a feature of construction applicable to double door elevators comprising two doors or clamping members, both of which are hinged to a single yoke section.

10 An object of the invention is to provide in a double door elevator a simple, yet effective, means for causing both doors to open simultaneously through the same angle with respect to the common yoke member to which they are hinged.

15 This application is a division of my application Serial No. 412,479, filed December 7, 1929.

20 In the accompanying drawings:

Figure 1 is a plan view of my elevator clamp in closed position;

25 Figure 2 is a horizontal section showing more clearly the mechanism for securing symmetrical motion of the doors;

Figure 3 is a rear elevation of the elevator; and

30 Figure 4 is a vertical section in a plane passing through the center of the clamp from front to rear.

Referring to Figure 1, my elevator comprises two main clamping members or jaws 1, which are hinged to a rear yoke 3 by pins 14. As shown in Figure 3, the pins 14 pass through ears 16 on the jaws of the clamp and ears 17 on the yoke 3. Handles 4 are formed on the front of the clamps whereby an operator can readily open or close them, and a latch mechanism, indicated generally at 5, is provided to lock the jaws in closed position. The latch mechanism 5 is fully described and claimed in my original application Serial No. 412,479. Latch mechanisms of different types are well-known in the art, and, since the particular type employed with the present invention is immaterial, it need not be described in detail.

35 In a double door elevator of the type described, it is desirable that the two halves of

the clamp open by equal amounts with respect to the center yoke 3 to which they are hinged. Various means have been employed in the past for securing this result. One expedient is to provide intermeshing gears on the clamping members 1 concentric with the pins 14, so that whenever one half of the clamp rotates with respect to the yoke 3, it causes a corresponding rotation of the opposite clamp about its axis.

40 In accordance with the present invention, I eliminate the necessity of using gears to produce symmetrical motion between the two halves of the clamps by providing a floating dog 18, positioned approximately midway between the hinge pins 14, that engages with the sides of recesses 19 in the ears 10 on clamps or door 1.

45 Referring particularly to Fig. 2 for an understanding of the operation of the invention, it will be observed that the rear lips 20 and front lips 21 of recesses 19 form openings only slightly wider than the thickness of the bar 18 so that if the operator opens only one door of the elevator the rear lip 20 on that door strikes bar 18 and forces it forward until the front side of the bar strikes the front lip 21 of the opposite recess and forces the opposite door to open simultaneously with the first. Similarly, if the operator closes only one door the front lip 21 on that door strikes the bar 18 and forces it against the rear lip 20 of the opposite door, causing it to close simultaneously with the first.

50 Since the door 1 swings through a rather large arc in opening, it is necessary to make the recesses 19 wider at their innermost ends than between the lips 20 and 21. Thus, as shown in Fig. 2, when the doors are open, the front faces of the recesses 19 lie substantially parallel to and in contact with the front face of bar 18. In the closed position of the doors the condition is reversed, since the ears 10 will have then swung through an arc such that the rear faces of recesses 19 lie parallel to and in contact with the rear face of bar 18.

55 The top and bottom faces of the recesses 19 and of the bar 18 are plane, parallel sur-

faces and their vertical dimensions are such that the bar fits loosely; hence its position within the recesses is determined solely by forces exerted upon it by lips 20 and 21.

6 The hinge construction described is simple and cheap to manufacture, cannot get out of order, and effectively performs the function of forcing the two doors to open and close simultaneously.

10 I claim:

1. An elevator of the character described comprising doors provided in their inner faces with concave recesses, a member positioned between and pivotally connected with 15 the doors, said doors being provided in their adjacent faces adjacent to the pivots with recesses, and a floating bar having its opposite ends positioned in the last mentioned recesses;
- 20 2. An elevator of the character described comprising doors provided in their inner faces with concave recesses and each provided with an ear, a member positioned between the doors, pivots connecting said member with the ears, said ears provided in their adjacent faces with recesses, and a floating bar having its opposite ends positioned in the last mentioned recesses;
- 25 3. An elevator of the character described comprising doors provided in their inner faces with concave recesses and each provided with an ear, a member positioned between the doors, pivots connecting said member with the ears, said ears provided with 30 plain convex adjacent faces with recesses in said faces, and a floating bar having its opposite ends positioned in the last mentioned recesses.

Signed at Los Angeles, California, this 4th
40 day of June, 1931.

NELSON K. SMITH.
